APPARATUS FOR CLEANING CARPETS AND
PILE FABRIC MATERIALS

George Elfers, Riverside, Calif.

Application March 2, 1936, Serial No. 66,647

1 Claim. (Cl. 15—89)

This invention relates to the method of and apparatus for cleaning carpets and pile fabric materials.

Among certain of the more important objects 5 in view, the following are given as illustrative, namely:

1. To provide a continuous method of cleaning pile fabrics while reeling and unreeeling the material;
- 10 2. To provide a continuous method of cleaning pile fabrics in which rapidly generated shaking impulses will be transmitted to the fabric opposite the pile side thereof, such as will effectively loosen all particles of dust and dirt therefrom and cause the pile to be restored to its original condition;
- 15 3. To provide a method of cleaning pile fabrics in which the material can be rapidly treated without injury thereto;
- 20 4. To provide a method of cleaning pile fabrics which will be wholly devoid of mechanical beaters;
- 25 5. To provide apparatus for cleaning pile fabrics in which a roll of material to be cleaned can be quickly associated with winding means such as will enable the fabric to be automatically rewound in operative time with the unwinding of the fabric and in operative time with the action of shaking mechanism;
- 30 6. To provide apparatus in which undulatory motions will be set up in the fabric within an effective zone, in which latter the loosened particles of dust can be ejected from the apparatus by induced suction;
- 35 7. To provide apparatus in which the cleaned fabric can be readily re-rolled onto a winding spindle positioned exteriorly of the cabinet of the apparatus;
- 40 8. To provide apparatus by means of which one end of the fabric to be cleaned can be readily threaded through the apparatus for co-operative association of the fabric with the shaking mechanisms and subsequently winding of the cleaned fabric;
- 45 9. To provide a method of cleaning fabric material wherein the front or starting end of the material can be first subjected to a shaking treatment throughout a period of time required to effect a thorough cleaning of said end and while all but said end of said material is confined against being drawn through the apparatus and the material then drawn through the apparatus at an effective speed and while subjecting successive or individual portions of the fabric to similar cleaning treatment;

10. To provide apparatus employing a rotary shaker, the direction of rotation of which can be readily changed to meet the foregoing requirements.

Other objects of the invention will be apparent as the purpose and operation of the invention are better understood and from an examination of the accompanying drawings, in which

Figure 1 is a view in partial section and elevation; 10

Figure 2 is an end view of the apparatus;

Figure 3 is a vertical transverse section through the machine showing the loose draping of the fabric material over the shaking member in dotted lines and showing in full lines the material passing from an unwinding roll to a winding roll; 15

Figure 4 is a transverse section through a portion of the apparatus showing the manner of re-winding the cleaned fabric upon a roll or 20 spindle exteriorly of the apparatus;

Figure 5 is a detail view of one of the end bearings for the supporting roll or spindle from which the fabric to be cleaned is adapted to be unwound; 25

Figure 6 is a detail view in elevation of portions of the winding spindle.

In carrying the invention into practice, use is made of a cabinet or enclosure 10 of any suitable well-known construction, from which the 30 dust and loose particles of dirt can be drawn off by suction through a duct 11. At the front, the cabinet is provided with a door 12 which can be tilted from the closed vertical position shown in Figure 3 to the opened position shown in full 35 lines in Figure 4. At the back, the cabinet is provided with a door 13 in order that access can be had to the interior of the cabinet for insertion of material to be cleaned. As shown, the material is in roll form wound on a spindle 40 14, removably mounted in end bearings, one of which is shown at B in Figure 5.

At 15 is shown a winding spindle, the supporting shaft 16 of which is journaled in bearings 17 in the ends of the cabinet. 45

Intermediate of the spindles 14 and 16 and disposed parallel thereto is a rotary shaft 18 having fixed thereto a shaking member 19. This member comprises a plurality of angularly related shaking elements 19a, preferably formed of 50 smoothly finished strips of maple, associated with each other to provide a long length, substantially rectangular structure, each element 19a thereof having an effective shaking extension 20, rounded at the fabric-contacting edge at 21. These 55

rounded extensions extend, respectively, at different lengths from the structure. The axes of the spindles 14 and 16 are preferably in a common diagonal plane with the axis of the shaking member 19, as shown in Figure 3, but it will be understood that changes in this relative disposition of the parts can be made without departing from the spirit of the invention. It is almost necessary, however, regardless of the relation of parts to each other, that the spindle 16 be disposed relative to the door 12 so that the fabric can be rewound onto a re-winding spindle 22, the end gudgeons of which (not shown) can be rotatably received in bearing brackets 23 adjacent to the ends of the cabinet and at the opposite sides of the door 12.

A gear system at one end of the cabinet is employed for the purpose of transmitting motion to the spindles 16 and 18 and, as shown, this system includes a suitable prime mover 24, such as a reversible electric motor in a power circuit 25, having a reversing switch 26. By selected adjustment of the switch, the shaft 27 of the motor can be driven either clockwise or counter-clockwise, as desired.

Trained over a small pulley 28 on shaft 27 and over a large pulley 29, the latter fixed to the spindle 18, is a drive belt 30. On a countershaft C is a small spur gear 31 adapted to mesh with a large spur gear 32 splined to slide on spindle 16. When said gears are meshed as shown in full lines in Figure 1, power is delivered to the spindle 16, to drive same at a low rate of speed, compared with the higher speed at which spindle 18 revolves. When, however, the gears are unmeshed, the spindle 16 may idle. Means 33 are employed for throwing the gear 32 into and out of mesh with the gear 31, the same co-acting with a latch or retaining device 34 in order that the selected adjustment of the gear 32 may be retained. Fixed to aforementioned countershaft C is a large gear 35 and meshing therewith is a small gear 36 on a countershaft C¹. Said shaft C¹ carries a sprocket gear 37 around which is trained a sprocket chain 38, the latter also passing around a sprocket gear 39 on the spindle 18.

On reference to Figure 3, it will be noted that the front or starting end of the roll of fabric F is loosely draped over the shaker member 19. Assuming that the motor 24 is running clockwise and that the gears 31 and 32 are unmeshed, the shaker member will revolve at high speed and as the free extremities of the strips 19a are, respectively, situated at different distances from the axis of the shaker, the front end of the fabric will be periodically contacted by the strips 19a and rapid undulatory motion imparted thereto throughout such time as shall be required to thoroughly clean said end. During this operation, the spindle 16 is not in rotation.

After the front end of the fabric is cleaned

as aforesated, the front end of the fabric is attached to the hooks 39 on the spindle 15. The gear 32 is now manually shifted into mesh with the small driven gear 31 on countershaft C. Assuming now that the motor 24 is running counter-clockwise, the shaker member 19 will also run counter-clockwise, and by reason of the gears 31, 32 and 36, the spindle 15 will be turned counter-clockwise, but at slow speed as compared to the speed of rotation of the shaker. It follows therefrom that the fabric will be slowly unreeled from the spindle 14 and successive portions thereof moved across the path of the strips 19a, there being sufficient slack in the fabric between the spindles 14 and 15 to enable effective rapid shaking of the exposed portion of said fabric and in operative time with the process of slowly winding the cleaned fabric onto the winding spindle 15.

After the fabric has been fully treated and entirely wound onto the spindle 15, the door 12 can be opened and the spindle 22 mounted in the bearing brackets 23 as shown in Figure 4. The outermost wound portion of the fabric can be passed from the spindle 15 and manually wound onto the spindle 22, a hand crank 40 on the latter making this easily possible.

I have now fully described the method of cleaning fabric materials and have likewise shown and described a new and novel machine by means of which the method can be practiced economically, thoroughly and quickly and with great ease and convenience. While I have referred to the cleaning of fabric materials generally, the method is particularly useful in the cleaning of floor coverings, such as rugs and carpets, and I wish particularly to call attention to the fact that when such pile fabric materials are being cleaned, the pile side of the material is placed outside or not facing the shaker 19. In consequence thereof, the pile is effectively loosened and restored to a more nearly normal state. The liberated dust is rapidly evacuated from the cabinet in time with operations of the shaker.

What is claimed is:

In a fabric cleaning machine, a shaker member; means mounting the shaker member to rotate about a fixed horizontal axis; the form of the shaker member being that of one having a pluralsided figure as its cross section, each side extending beyond its intersection with an adjacent side, and with such extensions of varying lengths, whereby to provide a plurality of fabric contacting strips; means for rotating the shaker; and means for feeding fabric along a path wherein the fabric will be supported and variably undulated by the successive contact of said strips with the fabric in order to effectively shake the fabric.

GEORGE ELFERS.
